DESIGN FOR AN ELECTRIC SWITCH HANDLE

Roger B. Kerr, Jamestown, R. I., and William G. Waggoner, Stamford, Conn., assignors, by mesne assignments, to The Trumbull Electric Manufacturing Company, a corporation of Connecticut

Application May 27, 1947, Serial No. 139,302

Term of patent 14 years

(Cl. D26—1)

To all whom it may concern:

Be it known that we, Roger B. Kerr and William G. Waggoner, citizens of the United States, residing respectively at Jamestown, in the county of Newport, State of Rhode Island, and Stamford, in the county of Fairfield, State of Connecticut, have invented a new, original, and ornamental Design for an Electric Switch Handle, of which the following is a specification, reference being had to the accompanying drawing, forming a part thereof.

In the drawing showing our design for an electric switch handle, Fig. 1 is a plan view; Fig. 2 is an elevation and Fig. 3 is an elevation of the

right end of the handle as shown in Figs. 1 and 2.

We claim:

The ornamental design for an electric switch handle, as shown,

ROGER B. KERR.
WILLIAM G. WAGGONER.
